PRESSURE RETAINING VALVE

Filed April 26, 1932

UNITED STATES PATENT OFFICE

PETER F. WILSON, OF CLEARLAKE, WASHINGTON

PRESSURE RETAINING VALVE

Application filed April 26, 1932. Serial No. 607,555.

This invention relates to pressure retaining valve mechanism for use with air brake systems of railway cars for the purpose of retaining a predetermined pressure in the brake cylinders after application of the brakes.

One object of this invention is the provision of a pressure retaining device for use with air brake systems which is under the control of the engineer and which is so constructed and arranged in the air brake system as to function to retain all or a part of the brake cylinder pressure while the auxiliary reservoir is being recharged.

Another object of this invention is the provision of a pressure retaining device controlled by train line pressure and adapted to retain all or a part of the brake cylinder pressure.

Still another object of this invention is the provision of a pressure retaining device for use with air brake systems of railway cars which is connected to the usual triple valve to automatically control the exhaust therefrom.

A further object of this invention is the provision of a pressure retaining device for air brake systems which is controlled by train line pressure and which is connected to the usual triple valve to automatically control the exhaust therefrom.

Other objects and advantages of this invention will be apparent from the following description taken in conjunction with the accompanying drawing in which:

Figure 1 is a fragmentary view showing the present invention in connection with a train pipe line main reservoir, triple valve and auxiliary reservoir, the view also showing more or less diagrammatically the brake valve and feed valve which are positioned for operation by an engineer.

Fig. 2 is a sectional view of the pressure retaining device of the present invention, and

Fig. 3 is a top plan view of the device shown in Fig. 2, the view having certain parts broken away to disclose other parts in section.

Referring now more specifically to the drawing and particularly to Fig. 1, the main reservoir is fragmentarily shown at 2 and the usual brake valve is indicated at 4 con-

nected to the main reservoir by a pipe 6. A feed valve, under the control of the engineer, is shown at 8 in a branch pipe 10 which leads from the pipe 6 into the brake valve 4. The train pipe line is indicated at 12 and is connected to the brake valve 4 by a pipe 14 and has connection with the usual type of triple valve 16 through a pipe 18, the triple valve 16 being connected to the auxiliary reservoir 20 to which latter the brake cylinder 22 is connected.

The retaining device forming the subject matter of the present invention is interposed in the system just described and is indicated generally at A and is connected to the exhaust 24 of the triple valve through a pipe 26. The device A is controlled in its operation by the train pipe line pressure and hence is connected through a pipe 27 with the pipe 18 leading from the train pipe line 12.

The device A comprises a body portion adapted to be connected at 30 to the pipe 26 so that the exhaust from the triple valve may pass into an exhaust chamber 32 formed in the body portion. On opposite sides of the chamber 32 are discharge valve chambers 34 and 36 respectively which are closed at their open ends by removable caps 38 and which contain escape valves 40 and 42 respectively which normally close ports 44 and 46 leading to plunger chambers 48 and 50. The valves 40 and 42 are adjustably secured to the upper end portions of stems 52 of plungers 54 arranged in the chambers 48 and 50 and seated on diaphragms 56 which close the lower open ends of said chambers and which are secured in position by removable caps 58 having supporting lugs 60 which extend upwardly from the concaved inner surfaces 62 of said caps and which serve to support the diaphragms at a central zone to limit the movement of the plunger 54 in one direction against movement of compression springs 64 which have one end of each thereof resting upon the plungers and the opposite or upper ends arranged in pockets 66 formed in spring adjusters 68 adjustably mounted within the plunger chambers 48 and 50. The stems 52 are provided at their upper ends with nuts 70 for securing the valves 40 and

42 against displacement. The spring adjusters 68 are provided with heads 72 having recesses 74 therein for receiving a suitable adjusting tool adapted to be inserted therein 5 through escape openings 76 formed in the body portion of the valve.

The valve chamber 34 is in constant communication with the chamber 32 through a port 78 and the chamber 32 is in communication with an upper valve chamber 80 through a port 82 normally closed by the resilient member 84 of a valve 86 formed with and secured to the lower end portion of a valve stem 88 which latter extends longitudinally in a valve housing 90 forming a part of the valve chamber 80 and secured to the body portion as at 92. The upper end of the housing is closed by a cap 94 and the valve stem 88 extends upwardly through a guide 96 adjustably mounted within the housing 90 as shown at 98 and having its under surface recessed as at 100 to form a pocket into which the upper end of a compression spring 102 is positioned, the spring 102 being interposed between said guide and the valve 86 and functioning to normally retain the valve in a position such as to close the port 82. The valve 86 is provided with a depending guide member 104 having vertical guide ribs 106 as clearly shown in Fig. 2. The valve chamber 80 communicates with the valve chamber 36 through a port 108.

The retainer device A, as before mentioned, is adapted to be controlled by train line pressure and the caps 58 are each provided with an inlet 110 through which train line pressure from pipes 12, 18 and 27 is passed through ports 112 into chambers 114 and 116, respectively, defined by the concaved inner surfaces 40 of the caps 58 and the diaphragms 56.

The valves 40, 42 and 86 are adapted to be unseated in response to predetermined pressures depending upon desired and required conditions. As an example, the spring adjuster 68 in plunger chamber 50 is adjusted to exert a pressure against spring 64 such that a pressure of approximately 68# is required in chamber 114 to shift the plunger 54 to unseat the valve 42, while the adjuster 68 in chamber 48 exerts a pressure against the spring in said chamber sufficient to require a pressure in chamber 116 of approximately 73# in order to unseat the valve 40. The spring 102 exerts compression against valve 86 to an amount sufficient to require a pressure of approximately 30# in exhaust chamber 32 to unseat the valve. In other words, the several valves in the body portion are adapted to be unseated in response to 55 different pressures, and preferably sequentially in response to increased pressures; valve 86 being the first to unseat; then valve 42 and finally valve 40.

It will be obvious that when the valve 86 is unseated communication is established be-

tween chambers 32 and 36 through port 108, and upon unseating of the valve 42 in response to pressure in chamber 114 communication is established from the chambers 32 and 36 to the atmosphere through port 46 and plunger chamber 50 and escape opening 76. Then, upon pressure at or above approximately 73# in chamber 116 the valve 40 is unseated and in addition to the above-mentioned escape of air to the atmosphere, it will be apparent that communication is established from chamber 32 through port 78 into valve chamber 34, then through port 44 into plunger chamber 48 and then to the atmosphere through the escape opening.

Train line pressure is controlled by the feed valve 8 which is so formed as to provide three predetermined pressures, namely, a high pressure preferably of approximately 80#, a low pressure of approximately 65# and an intermediate pressure of approximately 70#.

In the system shown in Fig. 1, air exhausting from the triple valve is discharged through pipe 26 into chamber 32 of the retaining device, and passes into valve chamber 34 and, if the pressure of the air in chamber 32 is above 30#, the valve 86 will be unseated and air will pass into chamber 80 and through port 108 into valve chamber 36. Air from the train line 12 can pass into the chambers 114 and 116 of the retaining valve structure due to their connection with the train line through pipe 27. It will be obvious that if the pressure in chamber 114 is above 68# the plunger 54 will be actuated to lift the valve 42 from its seat to permit the air in chamber 36, and hence the air in chambers 80 and 32, to escape to the atmosphere through plunger chamber 50 and escape opening 76 until the pressure in chamber 32 drops below 30#. The air from pipe 27, as mentioned above, passes into the chamber 116 and if the air is insufficient to establish or maintain a pressure in chamber 116 above 73# the valve 40 will remain seated, but upon increase of pressure in chamber 116 above 73#, the valve 40 will be unseated and it will be apparent that air exhausting from the triple valve through pipe 26 into exhaust chamber 32 can pass immediately to the atmosphere through port 78, valve chamber 34, port 44 and plunger chamber 48. It will be apparent that due to the ready and free escape of air from the triple valve when the valve 40 is unseated the brakes may be fully released.

To fully set the brakes and retain all the brake cylinder pressure while the auxiliary reservoir 20 is being recharged, a train line reduction of approximately 20# is made in the usual manner and the feed valve 8 is turned to its low pressure position and the brake valve 4 is operated to "running position." Due to the low pressure position of the feed valve the pressure in the train line will be approximately 65# which is insuffi-

cient to actuate either the valves 40 or 42 as above pointed out and hence there can be no exhaust from the triple valve to the atmosphere and the auxiliary reservoir 20 will be 5 recharged.

To partly release the brakes, the feed valve 8 is turned to the intermediate position, which, by way of illustration, is indicated by an arrow in Fig. 1, and this allows the train 10 line and chambers 114 and 116 to be charged up to 70#, which obviously is sufficient to actuate the diaphragm 56 to cause the plunger 54 in chamber 50 to be moved to unseat valve 42 whereby the air in chambers 36, 80 15 and exhaust chamber 32 passes to the atmosphere until the pressure in chamber 32 drops to 30#.

To fully release the brakes, the feed valve is turned to the "high-pressure position" to 20 permit the train line and chambers 114 and 116 to be charged with air in excess of 73# (about 80#, as described herein) which obviously will unseat the valves 40 and 42 and air exhausting through pipe 26 from the 25 brake cylinder and triple valve can pass immediately to the atmosphere through chambers 32, 34 and 48.

From the above description it is believed that the construction and operation of the 30 retaining valve structure of the present invention will be fully apparent to those skilled in the art without further elaboration. The drawing discloses one embodiment of the invention but it is to be understood they are 35 for illustrative purposes only and various changes in the form and proportions of the invention may be made within the scope of the appended claims without departing from the spirit of the invention.

40 What is claimed is:

1. In an air brake system in combination with the train line, auxiliary reservoir and triple valve, a pressure retaining device connected with the triple valve to receive exhaust 45 therefrom, said device including a body portion connected with the train line and having a plurality of valves therein normally preventing release of the triple valve exhaust from the device, said valves being so arranged and mounted as to be independently operable sequentially in response to progressively increased train line pressure.

2. In an air brake system in combination 55 with the train line, auxiliary reservoir and triple valve, a pressure retaining device connected with the triple valve to receive exhaust therefrom, said device comprising a body portion having an exhaust chamber therein, a 60 valve normally closing the chamber against escape of the exhaust and operable upon increase of air pressure in the chamber above a predetermined degree, a plurality of escape valves in the body portion, and means connecting the device with the train line to re-

ceive pressure therefrom to effect sequential operation of said escape valves in response to progressively increased pressure from the train line to effect venting of the exhaust out of the device. 70

3. A pressure retaining device for air 75 brake systems comprising a body portion having an exhaust chamber therein for receiving exhaust from a triple valve, a plurality of independently functioning valves in the body portion for controlling release of the triple valve exhaust to the atmosphere, valve chambers in the body portion normally closed by said valves, and means for adjusting said valves to cause the same to be operative in response to progressively increased air pressure thereagainst. 85

4. A pressure retaining device for air 90 brake systems comprising a body portion having an exhaust chamber receiving exhaust from a triple valve, a plurality of valve chambers each adapted to receive triple valve exhaust from the exhaust chamber, one of said chambers being in constant open communication with the exhaust chamber, valve means for controlling passage of triple valve exhaust to the other valve chambers, escape valves normally preventing release of the exhaust from the body portion, means connecting said device to the train line whereby the latter is adapted to receive pressure therefrom to operate said escape valves, and means for adjusting the escape valves to operate respectively in response to different train line pressure to control escape of the triple valve exhaust from the device. 100

5. In an air brake system in combination 105 with the auxiliary reservoir, triple valve and train line, a pressure retaining device comprising a body portion having an exhaust chamber therein receiving exhaust from the triple valve, a plurality of escape valve chambers in the body portion one thereof being in constant open communication with the exhaust chamber, a valve normally preventing passage of exhaust to the other valve chambers operable upon increase of pressure in the exhaust chamber to permit escape of exhaust into the other escape valve chamber, 110 valves in the escape valve chambers normally preventing escape of the exhaust from said body portion, and means connecting the train line and body portion to pass air into the body portion to actuate the escape valves. 115

6. In an air brake system in combination 120 with the auxiliary reservoir, triple valve and train line, a pressure retaining device comprising a body portion having an exhaust chamber therein receiving exhaust from the triple valve, a plurality of escape valve chambers in the body portion one thereof being in constant open communication with the exhaust chamber, a valve normally preventing passage of exhaust to the other valve chamber. 125 130

bers operable upon increase of pressure in the exhaust chamber to permit escape of exhaust into the other escape valve chamber, valves in the escape valve chambers normally preventing escape of the exhaust from said body portion, means for adjusting the escape valves to permit respective operation thereof only in response to progressively increased pressures, and means connecting the train line and body portion to permit passage of air from the train line into the body portion to actuate the escape valves.

7. In a pressure retaining device for air brake systems, a body portion having an exhaust chamber for receiving exhaust from a triple valve, discharge chambers in said body portion one thereof being in constant open communication with the exhaust chamber, an exhaust valve chamber in constant open communication with the other discharge chamber and having a port communicating with the exhaust chamber, a spring pressed valve normally closing the port to prevent escape of triple valve exhaust into the exhaust valve chamber, means for adjusting the valve spring whereby said valve is operative only in response to predetermined pressure in the exhaust chamber, spring pressed escape valves in the said discharge valve chambers, said body portion having expansible pressure chambers therein for receiving air under pressure to actuate the escape valves to permit release of triple valve exhaust to the atmosphere.

8. In a pressure retaining device for air brake systems comprising a body portion having a valve operative in response to train line pressure, a plunger chamber in the body portion provided with an expansible air chamber at one end thereof, a plunger in said chamber to which the valve is secured, said plunger seating on the air chamber, a spring adjuster in the plunger chamber adapted to guide the plunger in its movements, and a spring interposed between said adjuster and plunger for normally urging the valve to seated position, said adjuster being movable in said chamber to exert a predetermined pressure on the plunger whereby the valve is adapted to be unseated only in response to predetermined air pressure within said air chamber.

9. A pressure retaining device for air brake systems comprising a body portion having spaced plunger chambers therein, removable covers for the chambers having means for connecting the same with the train line, flexible diaphragms closing the open ends of said chambers, said diaphragms being secured in position by said covers and forming with the latter air chambers for receiving train line pressure, valve chambers in said body portion having ports connecting the same with the plunger chambers, spring

pressed plungers in the plunger chambers seated on the diaphragms and provided with valves at their upper end portions normally closing the ports in the valve chambers, an exhaust chamber connected to receive exhaust from the triple valve of the system and in constant open communication with one of the before mentioned valve chambers, a valve normally preventing passage of the triple valve exhaust to the ported valve chamber, means for guiding the valves during their movement, said means being adjustable to vary the compression of the springs whereby said valves are adapted to operate only in response to predetermined air pressures.

In witness whereof I have hereunto set my hand.
